UNITED STATES PATENT OFFICE.

EDWARD KRANTZ, OF CHICAGO, ILLINOIS.

DESIGN FOR A CASING FOR A CARPET-CLEANER.

50,310.

Specification for Design.

Patented Feb. 13, 1917.

Application filed April 15, 1916. Serial No. 91,488. Term of patent 3½ years.

To all whom it may concern:

Be it known that I, EDWARD KRANTZ, a citizen of the United States, residing in the city of Chicago, in the county of Cook and State of Illinois, have invented a new, original, and ornamental Design for a Casing for a Carpet-Cleaner, of which the following is a specification, reference being had to the accompanying drawings, forming part thereof.

10 In these drawings Figure 1 is a top plan of the cleaner casing embodying the design; and

Fig. 2 is a side elevation of the same.

I claim:

The ornamental design for a casing for a carpet cleaner substantially as shown.

EDWARD KRANTZ.
